UNITED STATES PATENT OFFICE.

ALEXANDER HUBBARD, OF LONDON, ENGLAND.

PROJECTILE.

1,302,167.

Specification of Letters Patent. Patented Apr. 29, 1919.

Application filed June 27, 1917. Serial No. 177,332.

To all whom it may concern:

Be it known that I, ALEXANDER HUBBARD, a subject of the King of Great Britain and Ireland, residing at 98 Leigham Court road, Streatham, London, S. W. 16, England, have invented a new and useful Projectile, of which the following is a specification.

This invention relates to projectiles, and has for its object the provision of an improved projectile which finds a special application for use under water although it is not limited in this respect, and the invention comprises the application of a new method of shooting into and through the water with accuracy of aim.

Hitherto the resistance offered by water to the passage of a body therethrough has been an effective bar to the use of projectiles which can be discharged from guns similar to those used above water and on land. Recourse has therefore been had to projectiles such as torpedoes which are self driven and do not depend to any great extent upon the force of the explosion which discharges them. Such projectiles are however costly and difficult to manufacture and according to the present invention an improved type of projectile which principally owing to its peculiar shape or form overcomes the resistance of the water which was hitherto thought to be insurmountable, is provided and which is dependent for its velocity entirely upon the force of an explosion which fires it from a gun similar in design to an ordinary breech loading field gun. A further feature of the improved projectile consists in the fact that it can be fired through the air and that when it strikes the water it will continue its motion without alteration of direction or trajectory. Further if desired the projectile can be used for land warfare, in which case a considerable gain in muzzle velocity and length of flight is obtained.

To enable the projectile to pierce the water with facility it is provided with helical blades or vanes disposed in the direction of its length, and being adapted to be fired from a rifled gun, the rotary movement imparted to the projectile will cause the blades to produce an effect similar to that of a screw propeller and impel the projectile through a much greater distance than would be possible with projectiles of any type usually fired from a gun.

The invention will now be described in connection with the accompanying drawings in which:—

Figure 1 is an elevation of the improved projectile. 60

Fig. 2 is a cross section through a gun barrel with a projectile therein.

Fig. 3 and Fig. 4 are sectional and end elevations respectively of an obturator used in firing the improved projectile. 65

Fig. 5 is a section through the forward end of the projectile showing the firing means.

The improved projectile consists of a central core or cylinder *a* which may taper slightly toward its forward end provided with helical blades *b* preferably four in number as shown. The edges of these blades may be bent into substantially right angle form as indicated at *c* with the object of 70 attaining the best possible propelling effect. The central portion or core *a* of the projectile is made hollow to contain an explosive charge adapted to be detonated when the projectile strikes against the side of a ship 75 or other solid body. For the purpose of effecting such detonation the projectile is provided with a suitable form of firing pin or needle *d*, one form of which is illustrated in Fig. 5, wherein the pin is prevented from 80 being operated by the pressure of the air or water through which it is passing by means of a spring *e*, the resistance of which is overcome however when the projectile strikes a 85 solid body, and the pin *d* is caused to detonate the cap *h* and explode the charge. 90

It will be understood that a propellant must be used which will explode with much greater violence than those used in ordinary guns in order to discharge the projectile 95 with a force sufficient to carry it through distances of such length as will render its use practicable. It will therefore be necessary to make the barrel *e* of the gun considerably thicker than those in ordinary use, 100 and having a rifled sleeve or lining *f* inserted therein the number of grooves *g* in which correspond with the number of blades *b*.

As will be seen from Fig. 2 the edges *c* of the projectile rest in the grooves *g* and to 105 prevent the force of the explosion escaping between the blades during firing use is made of the obturator shown in Figs. 3 and 4 and which comprises a disk *h* adapted to fit tightly within the lining *f*. This disk car- 110

ries on its periphery a number of lugs or splines *i* adapted to fit closely within the grooves *g*, and thereby prevent the waste of any products of the explosion.

5. The lugs or splines *i* are disposed on one side only of the obturator which on that side is concave in form as shown in Fig. 3. This concave side of the obturator is disposed toward the breech of the gun and the propelling charge is disposed in proximity thereto.

When the gun is fired the projectile and the obturator will be discharged therefrom in close proximity to one another and having a rotary as well as a forward motion due to the action of the rifled grooves in the barrel. The passage of water between the blades of the propeller however quickly detaches the obturator owing to the resistance offered by its flat circular surface while the projectile pursues its way assisted by the propeller like action of its blades.

20. The improved projectile may be fired from a gun beneath the water, or may be caused to dive into the water from a gun on a ship or on land, but in the former case means are provided to prevent an inrush of water into the barrel of the gun after firing.

25. If desired the improved projectile may be fitted with any convenient and (or) known form of time fuse and detonating device and this will particularly be necessary where the projectile is used for land warfare. It has been found that where the whole of the flight is through the air a very much longer range is obtained, combined with a flatter trajectory than is usual with projectiles of known construction.

30. I claim:—

1. A projectile comprising a hollow tapering tube, four helical blades arranged on the outside of said tube extending from end to end thereof and terminating in a flat head.

40. 2. A projectile comprising a hollow tapering tube, helical blades arranged on the outside of said tube extending from end to end thereof, said blades being attached to the tube at points situated at ninety degrees from one another.

45. 3. A projectile comprising a hollow tapering tube, helical blades arranged on the outside of said tube extending from end to end thereof, said blades being attached to the tube at points situated at ninety degrees from one another, and terminating in a flat head.

50. 4. A projectile comprising a hollow tapering tube, four helical blades arranged on the outside of said tube extending from end to end thereof, said blades being attached to the tube at points situated at ninety degrees from one another.

55. 5. A projectile comprising a hollow tapering tube, four helical blades arranged on the outside of said tube extending from end to end thereof, said blades being attached

to the tube at points situated at ninety degrees from one another, and terminating in a flat head.

6. A projectile comprising helical blades arranged on the outside and extending from 70 end to end of a hollow tube the edges of said blades being turned over at right angles.

7. In a projectile the combination of a hollow tapering body, helical blades disposed on the outside and extending from 75 end to end of said body, a flat head to said projectile, detonating means disposed in said head, an explosive charge disposed within said body, and a spring retarding device normally restraining said detonating 80 means.

8. In a projectile the combination of four helical blades arranged on the outside of a hollow tube, said helical blades extending from end to end of the projectile, a flat head 85 to said projectile, and edges extending at right angles from said blades.

9. In a projectile, a hollow tapering tube, four helical blades arranged on the outside, and extending from end to end of said tube, 90 said blades being attached to said tube at points situated at ninety degrees from one another and having their edges turned over at right angles, and said projectile having a flat head.

10. In a projectile the combination of a hollow tapering body, four helical blades disposed on the exterior and extending from 100 end to end thereof, attached at points situated at ninety degrees from one another, edges extending at right angles to said blades, an explosive charge disposed within said body, detonating means disposed in the head of said projectile, and means normally operative to prevent premature detonation 105 of said charge.

11. In a projectile the combination of a hollow tapering body, four helical blades disposed on the exterior and extending from 110 end to end thereof, attached at points situated at ninety degrees from one another, edges extending at right angles to said blades, a flat head to said projectile, an explosive charge disposed within said body, a detonating pin disposed in said head, and 115 a spring retarding device normally restraining said detonating pin.

12. In a projectile, helical blades arranged on the exterior of a hollow body, extending from end to end of said body, a flat head 120 terminating said body and blades, edges extending at right angles from said blades, detonating means disposed in said head, an explosive charge disposed within said body, and means for preventing premature operation 125 of said detonating means.

13. In a projectile, four helical blades arranged on the exterior of a hollow body, a flat head terminating said body extending from end to end of said body and blades, 130

edges extending at right angles from said blades, a detonating pin disposed in said head, an explosive charge disposed within said body, and a spring retarding device normally operative against premature operation of said detonating pin.

14. A projectile comprising a tapering tube containing an explosive charge and means for detonating said charge, four helical blades arranged on the exterior and ex-

tending from end to end of said tube, and a flat head terminating said tube and blades.

In testimony whereof I have signed this specification in the presence of two subscribing witnesses.

ALEXANDER HUBBARD.
